FLATTENING OF EXTRUDED STIFFENED SHEETS

Giuseppe Cozzo, Yonkers, N. Y., assignor to Hydropress, Incorporated, New York, N. Y., a corporation of Delaware

Application December 22, 1951, Serial No. 262,987

6 Claims. (Cl. 29—155)

1

This invention relates to the making of flat integrally stiffened sheets and particularly to flat sheets made from tubes having ribs integrally joined thereto.

Integrally stiffened sheets are ones having a plurality of ribs projecting from the flat portion of the sheet, said ribs usually being substantially parallel to each other and having a flange. The integrally stiffened sheets can be used for numerous purposes where a light weight yet stiff panel or sheet is needed. As an example, such a sheet finds use in the wing of an airplane, truck panels, and other similar uses. The sheets can be made of a light metal. One of the problems involved in the forming of such a sheet is that of making it so that it is perfectly flat. When the T-shaped ribs thereon are integral with the metal of the flat portion of the sheet, such eliminates riveting or similar joining operations. One of the biggest problems is that of making the sheet so that it will be substantially flat where the rib joins the flat portion of the sheet.

One of the objects of the present invention is to form integrally stiffened sheets which will be substantially flat when finished.

Another of the objects of the invention is to provide an improved method of making integrally stiffened sheets from tubes.

In one aspect of the invention, a shaped tube can be formed by extruding metal through a suitable die, the extruded tube having radially projecting ribs extending longitudinally along the tube. The ribs can be made the size and shape to produce the desired ribs in the finished sheet. The ribs may have webs joined to the sheet and a flange.

The extruded tube can be fed into a tube advancing means which moves the tube into a slitter which cuts through one side of the tube. The slit tube then can be fed through one or more opening roller die means which can be arranged to progressively change the shape thereof from that of a tube to that of a flat sheet.

The flattened sheet then can be fed to a special roller die arrangement for particularly flattening the sheet adjacent the ribs. This last mentioned roller die arrangement can have a backing roller or guide arranged so as to bear on the flat side of the sheet opposite the rib side and can have recesses or annular spaces opposite the ribs. Roller means may be provided bearing on the ribbed surface side of the flat sheet, these rollers at least bearing on the surface closely adjacent where the webs of the ribs join the sheet. Rolls for the rib flanges can be provided for exerting

5 pressure on the top of the rib or flange, the flange roller pressing its flange and web toward the recess or annular space of the backing roller. This will serve to flatten the area adjacent the web joint.

10 The flattened sheet then can be passed through a special pulling and pushing roller die means. Next, the sheet can be flexed in a flexing roller die means to overcome residual bending. This die means is for the purpose of neutralizing the tendency of the flattened sheet to return to its curved shape. Preferably, the flexing roller die means is constructed so as to be adjustable in accordance with the particular material and 15 sheet involved.

These and other objects, features, and advantages of invention will become apparent from the following description and drawings.

In the drawings:

20 Fig. 1 shows a fragmentary side view partially in section of one form in which the invention can be arranged and carried out.

Fig. 2 is an enlarged sectional view of one type of tube from which integrally stiffened sheet can be made.

25 Fig. 3 is an enlarged fragmentary view of one of the progressive opening roller arrangements, such as the one indicated at line 3—3 of Fig. 1.

Fig. 4 is an enlarged fragmentary sectional view of the rib area flattening roller die located 30 at line 4—4 of Fig. 1.

Fig. 5 is an enlarged schematically illustrated 35 pulling and pushing roller die mechanism, such as can be located at line 5—5 of Fig. 1.

Fig. 6 is an enlarged fragmentary view of the flexing mechanism as can be located at line 6—6 of Fig. 1.

40 The sheet can be made from a tube formed in suitable extrusion machines. As an example, the metal involved can be aluminum, aluminum alloy, or other light-weight alloy or metals. The radially projecting ribs are made of such dimensions that when the tube is flattened, the final sheet will have the desired characteristics and dimensions. In Fig. 2, one form of tube shape is shown at 10 which can have radially extending or projecting ribs 11 integrally formed with the walls 12 of tube 10. Ribs 11 may have webs 13 joining the flanges 14 to the wall 12 of the tube.

45 The tube 10 can be fed into the arrangement of Fig. 1 in any suitable manner such as over the rolls of conveyor 15 into the feed pinch rolls 16. A suitable cutter 17 slits the wall of the tube and wedge 18 tends to open the tube.

50 A succession of opening roller die means 19A—

19F, inclusive, then can be located along the machine for the purpose of flattening the tube. One or more such opening means can be used as needed. As an example of one form of opening means, reference may be made to Fig. 3 wherein the upper rolls 20 can be located on shaft 21 which can be suitably driven. Rolls 22 can be located on either side of the center group of rolls, rolls 22 being mounted on driven shafts 23 schematically shown in Fig. 3. Rolls 20 pass between ribs 11 and bear on the upper surface of the flat portion of the sheet. A backing roll 24 can be mounted on shaft 25, said backing roll not being driven. Edge supports 26 can be mounted on shafts 27 on either side of the sheet. The opening rolls 19A through 19F are arranged suitably and are constructed so that the parts have the correct relationship to each other, and so that at 19F the sheet will be substantially flat and ready to pass to special roller die means for completing the flattening of the sheet.

The roller die means at 4—4 of Fig. 1 has roll means between each of the webs. In one form, each bracket 28 thereof can be fastened on a mechanism (not shown) for moving it in the direction of arrows 29. Bracket 28 carries a shaft 30 mounted in suitable bearings 31, said bearings being in the form of needle bearings, or the like. At the ends of shaft 30, formed rolls 32 can be arranged so that they will press the upper face 33 of the flattened wall or flat sheet portion of 12 at a point close to web 13 of rib 11. A backing roll 34 may have annular recesses 34A located under each of the webs 13. Rib or flange roll means 35 can be suitably mounted on a shaft (not shown) which can be pressed downwardly on flanges 14 of ribs 11. It can be theorized that because of the pressure exerted on the ribs and the recesses thereunder, in conjunction with the closeness of roll means 32 to the joinder of the webs with the flat portions of the sheet, that the metal will be shaped in these areas in a manner that will result in a substantially flat sheet. In other words, the metal of the sheet close to the web junction will be formed into a substantially flat shape.

At the next station in Fig. 1, a pinch roll sheet moving arrangement, such as illustrated in Fig. 5, can be employed. In the form shown, two sets of drive roll means are employed, it being understood that any number can be used or that they can be located as needed. Rolls 36 are mounted on shaft 37 which can be driven by suitable driving mechanism. Rolls 36 extend between the ribs and grip the flat portion of the sheet between them and the backing roll 38. Backing roll 35 can be carried on shaft 39.

The flattened sheet can be moved from driving mechanism rolls 36 to an adjustable flexing roller die means for overcoming residual bending or the tendency of the sheet to return to the original tube shape. One form of such a means is illustrated in Fig. 6 and can be located at line 6—6. Each of the upper rolls 40 can be carried on a shaft 41 mounted in a bifurcated arm 42. Arm 42 may be adjustably carried by yoke 43, the arm being adjustably mounted thereon by bolt and nut 44 passing through the elongated slot 45 in arm 42 and elongated slot 46 in yoke 43. Thus, each of the arms 42 is mounted in such a manner that it can be moved as desired to provide the correct flexing of the sheet. Rolls 40 bear upon the upper face of the flat portion of the sheet.

Backing rolls 47 can be carried on roller bear-

ings 48 which in turn can be mounted on carriers 49. Carriers 49 may have square or suitable shaped apertures through which pass the laminated or flexible shaft or support 50. Support 50 is so arranged that it can be suitably flexed in accordance with the desired curvature to which the sheet is to be bent or flexed. Spacers 58 can be provided between the backing rolls as needed. The ends of support 50 can be held by bolts 51 in brackets 52, brackets 52 being in effect pivoted at point 53 of the abutment 54. Point 53 of abutment 54 is engageable in a suitable notch 55 in the arms of yoke 43. Nuts 56 and lock nuts 57 can be provided in order to suitably adjust the mechanism according to the curvature desired.

It is to be understood that parts of the combination can be used and that variations may be made in the details of construction without departing from the spirit of the invention except as defined in the appended claims.

What is claimed is:

1. In an apparatus for producing flat integrally stiffened sheets having projecting ribs from a slit tube, the combination including tube flattening means receiving said slit tube and at least partially flattening the same, roller die means having roll means exerting pressure between said ribs on the rib side of said sheet and closely adjacent where said ribs join said sheet, and backing means on the smooth side of the ribbed sheet opposing said roller die means.

2. In an apparatus for producing flat integrally stiffened sheets having projecting ribs from a slit tube, the combination including tube flattening means receiving said slit tube and at least partially flattening the same, roller die means having roll means extending between said ribs exerting pressure on the rib side of the sheet close to the points where said ribs join said sheet, means simultaneously exerting pressure on said ribs in the same direction as that of the pressure applied to the sheet, and backing roll means bearing against the smooth side of the ribbed sheet opposing said roller die means.

3. In an apparatus for producing flat integrally stiffened sheets having projecting ribs from a slit tube, the combination including tube flattening means receiving said slit tube and at least partially flattening the same, roller die means having roll means extending between said ribs and exerting pressure on said sheet, said roller die means having a plurality of rolls extending between said ribs and contacting the rib side of said sheet closely adjacent the joinder point of said ribs with said sheet and exerting pressure thereon, backing roll means bearing against the opposite side of the sheet and having relieved portions opposite said ribs, and roll means exerting pressure on said ribs in the same direction as that of the pressure on the sheet at the same time as said roller die means so as to flatten said sheet.

4. In an apparatus for operating on integrally stiffened sheets having projecting ribs, the combination including a plurality of rolls having sheet contacting surfaces passable between the ribs for contacting the flat surface of the sheet, means adjustably supporting each of said rolls so that the sheet contacting surfaces of the rolls will define a predetermined curvature, backing rolls for the aforementioned rolls, carrier means for each of said backing rolls, said carrier means having an aperture therethrough, and a flexible

shaft means passing through said carrier means and supporting said backing rolls in the desired curvature in relation to said first mentioned rolls.

5. The method of forming a flat integrally stiffened sheet member having a sheet portion and a plurality of integral substantially parallel ribs projecting therefrom, comprising the steps of slitting a tube having ribs extending radially from the wall of said tube, then flattening the ribbed wall by exerting pressure on the rib side of said sheet portion at the surface thereof closely adjacent to the points where the ribs join the sheet portion, and at the same time exerting pressure on said ribs toward said sheet while supporting said sheet portion on the side of said sheet opposite to the ribs.

6. The method of forming a flat integrally stiffened sheet member having a plurality of integral projecting ribs, comprising the steps of slitting a tube having ribs radially extending from the wall of said tube, progressively opening said slit tube and flattening said ribbed wall by exerting pressure thereon close to the points where the ribs join the wall on the rib side of said wall while supporting the opposite side of

said wall, and thereafter flexing said wall in a direction opposite to its curvature as a tube.
